H. A. TOUSSAINT,
PERMUTATION LOCK,
APPLICATION FILED AUG. 26, 1916.

1,228,264.

Patented May 29, 1917.

UNITED STATES PATENT OFFICE.

HUGHEY ALBERT TOUSSAINT, OF CASEYVILLE, ILLINOIS.

PERMUTATION-LOCK.

1,228,264.

specification of Letters Patent. Patented May 29, 1917.

Application filed August 26, 1916. Serial No. 117,004.

To all whom it may concern:

Be it known that I, HUGHEY A. TOUSSAINT, a citizen of the United States, and a resident of Caseyville, in the county of St. Clair and State of Illinois, have invented a certain new and useful Improvement in Permutation-Locks, of which the following is a specification.

My invention is an improvement in permutation locks, and has for its object to provide a lock of the character specified especially adapted for locking fly wheels and the like, wherein a bolt is provided and a casing in which the bolt is mounted and adapted to be arranged on a fixed support adjacent to the wheel, the bolt having a shoe for engaging the wheel to lock the same, and wherein interlocking mechanism is provided in connection with the bolt and the casing, for holding the bolt in locked position.

A further object is to provide a lock of the character specified adapted for use in any connection as a longitudinally movable bolt having locking means, as specified.

In the drawings:

Figure 1 is a side view of the improved lock, in locked position;

Fig. 2 is a front view in unlocked position;

Fig. 3 is a section on the line 3-3 of Fig. 2, looking in the direction of the arrows adjacent to the line;

Fig. 4 is a section on the line 4-4 of Fig. 3, looking in the direction of the arrows adjacent to the line;

Fig. 5 is a perspective view of the bolt, and

Fig. 6 is a similar view of one of the tumblers.

The present embodiment of the invention is shown in connection with a fly wheel 1 of a motor 2, the fly wheel having a series of peripherally arranged teeth 3 with which the lock cooperates. The lock comprises a bolt 4 of suitable length and cross section, having at one end a head 5 and provided at the other with a shoe 6 having teeth for engaging the teeth 3. This shoe is shown as provided with a socket or recess for receiving the end of the bolt, and a set screw 7 is threaded through the shoe into engagement with an opening in the bolt to hold the parts in position.

The bolt is mounted to move longitudinally in a casing 8 which has a bore 9 for

receiving the bolt. The bore extends entirely through the casing, and the casing is provided with a reamed-out or enlarged portion 10, the said portion opening at opposite sides and at the front of the casing, and being designed to receive the rotatable tumblers to be described. At the rear the casing has a lug 11 which is adapted to receive a clip or staple 12 on the motor 2.

A series of ring-shaped tumblers 13 is arranged within the recess or counterbored portion 10, in superposed relation, and with the bolt passing through the central opening of the tumblers. Each of these tumblers is provided on its peripheral surface with a series of symbols 14, letters in this instance. Each of the tumblers 13 is provided on its inner surface with an inwardly extending lug 15, and these lugs are adapted to move in annular grooves 16 in the bolt and in a longitudinally extending groove 17 which intersects all of the annular grooves and extends to the end of the bolt provided with the shoe. The grooves 16 are spaced apart and fit and receive the lugs 15 when the tumblers are in superposed position, and it will be obvious that while the tumblers are in the annular grooves, the bolt cannot move longitudinally until all of the lugs 15 are in register with the longitudinal groove 17. When this occurs, the bolt may be moved longitudinally into the position shown in Figs. 1 and 3.

In use, when it is desired to lock the wheel with the parts in the position of Figs. 2 and 3, the tumblers are rotated until all of the lugs 15 are in register with the groove 17. The bolt may now be moved toward the wheel to cause the teeth of the shoe 6 to engage with the teeth 3 of the wheel. When now the tumblers 13 are turned to bring the lugs 15 out of register with the groove 17, and into the grooves 16, it will be obvious that the bolt will be locked against longitudinal movement until the lugs are again brought into register with the longitudinal groove.

In order to permit the tumblers to be brought into a predetermined position, that is, with the lugs 15 in register, the letters on the periphery of each tumbler are arranged in a certain predetermined manner with respect to the lug, so that when a certain predetermined arrangement of letters is brought into register with one edge of the opening 10 or with an indicator on the cas-

ing, the said lugs will be brought into register with the groove 17. For instance, the arrangement might be such that, when the lugs were in register with the groove 17, a 5 certain word might be spelled by the letters with the tumblers at a predetermined point.

It will be obvious that without the shoe 10 the lock might be used as an ordinary bolt engaging a hasp on the door or an opening in the door, or in any other connection where a longitudinally movable bolt is desired.

When the bolt is used for a door, for instance, the innermost annular groove forms 15 a guide for the proper placing of the bolt, since the lug and the innermost tumbler cannot move beyond the groove. The casing is provided with an inwardly extending lug 18 which moves in the groove 17 to prevent rotation of the bolt.

20 It will be observed that the bolt is rotatable in the casing and with respect to the tumblers, in either the position of Fig. 1 or that of Fig. 3, that is when the bolt is in locking position or in unlocking position.

25 Thus to prevent unauthorized locking of the bolt when it is desired that the bolt remain unlocked, it may be given a half turn from the position shown in Figs. 1 and 2, and

before the bolt can be locked, it must be re- 30 turned to original position.

I claim:—

A permutation lock comprising a casing having a bore enlarged at one end to form a tumbler receiving chamber opening at the front of the casing, a bolt slidable and rotatable in the bore, a series of ring-shaped tumblers in the enlargement and encircling the bolt, each tumbler having an inwardly extending radial lug, the bolt having an annular groove for each tumbler and an 40 additional annular groove, said grooves being spaced to correspond with the spacing of the lugs of the tumblers and adapted for engagement by said lugs to hold the bolt in locking or unlocking position, and a longitudinally extending groove intersecting the annular groove stopping short at the innermost of the grooves to provide a limiting means for the outward movement of the bolt by the engagement of the lug of the innermost tumbler with the inner wall of the 45 innermost groove.

HUGHEY ALBERT TOUSSAINT.
